UNITED STATES PATENT OFFICE

126,092

DESIGN FOR A COMBINATION DESK UNIT

Warner Hoople, Chicago, Ill., and Marlin S. Baker
and Ivan D. Tefft, Janesville, Wis., assignors to
The Esterbrook Steel Pen Manufacturing Co.,
Camden, N. J., a corporation of New Jersey

Application January 2, 1940, Serial No. 89,258

Term of patent 14 years

To all whom it may concern:

Be it known that we, Warner Hoople (1), Marlin S. Baker (2) and Ivan D. Tefft (3), citizens of the United States of America, and residents of (1) Chicago, Illinois, and (2 and 3) Janesville, Wisconsin, have invented a new, original, and ornamental Design for a Combination Desk Unit, of which the following is a specification, reference being had to the accompanying drawing, forming a part thereof.

Figure 1 is a perspective view of the combination desk unit showing our new design;

Figure 2 is a plan view thereof; and

Figure 3 is a side elevational view of the same.

We claim:

The ornamental design for a combination desk unit, substantially as shown.

WARNER HOOPLE.
MARLIN S. BAKER.
IVAN D. TEFFT.
